LOCKING DEVICE

Charles J. Glatt, Philadelphia, Pa.

Application October 17, 1947, Serial No. 780,559

1 Claim. (Cl. 292—138)

(Granted under the act of March 3, 1883, as amended April 30, 1928; 370 O. G. 757)

1

The present invention concerns a sliding-bolt lock and particularly concerns a lock of such type actuated by a key that can be screwed through a threaded opening in the elements supporting the bolt and screwed into a threaded hole in the extremity of the bolt.

An object of the invention is to provide a sliding-bolt lock in which the bolt in locking position is substantially enclosed by the elements locked together and access to the bolt is through a restricted opening in alignment with the bolt and formed in the element supporting and enclosing the bolt.

A further object is to provide a sliding-bolt lock in which the bolt in locking position is substantially enclosed by the elements that are locked together and access to the bolt is through a restricted threaded opening in alignment with the bolt and formed in the element supporting the bolt.

A further object is to provide a sliding-bolt lock in which a bolt in locking position is substantially enclosed by the elements that are locked together, access to the bolt being through a restricted opening in alignment with the bolt and formed in the elements supporting the bolt, the extremity of the bolt adjacent the opening being provided with means for engaging a key insertable through the opening.

A further object is to provide a sliding-bolt lock in which the bolt in locking position is substantially enclosed by the elements that are locked together, access to the bolt being through a restricted threaded opening in alignment with the bolt and formed in the element supporting the bolt, the extremity of the bolt adjacent the opening being provided with a threaded hole in alignment with the threaded opening, the bolt being adapted for actuation by a key having a threaded extremity which can be screwed through the opening and into the bolt hole.

Further objects and advantages of this invention, as well as its construction, arrangement and operation, will be apparent from the following description and claim in connection with the accompanying drawing, in which the single figure of the drawing is a sectional view showing a preferred embodiment of the present invention with the sliding bolt in locking position.

There is shown an upper sash 11 and a lower sash 12 forming part of a conventional window construction. Upper sash 11 is provided with a seat 13 that accommodates a barrel 14 having an internal bore 15. The right end of barrel 14 as seen in the figure is flared at 14a and opens to

2

the exterior of upper sash 11 and the left end of barrel 14 terminates in the interior of upper sash 11 and is closed thereby. Lower sash 12 is provided with a seat 16 that accommodates a barrel 17 having an internal bore 18. The left end of barrel 17 as seen in the figure opens to the exterior of lower sash 12 and the right end of barrel 17 is closed by a transverse wall 19, the outer surface of which is flush with the exterior surface of lower sash 12. A threaded opening 20 is provided in transverse wall 19. Preferably bores 15 and 18 are circular.

Disposed for sliding movement within bore 18 is an elongated bolt 21 of substantially the same circular shape as bores 15 and 18. Bolt 21 is of substantially the same or slightly less length than barrel 17 so that bolt 21 can be withdrawn to the right of the position shown in the figure to be completely enclosed within barrel 17 in retracted or unlocked position. In locked position as shown in the figure bolt 21 projects externally of barrel 17 into bore 15 of upper-sash barrel 14. The left end of bolt 21 is chamfered at 22 to facilitate penetration into barrel 14. The right end of bolt 21 is formed as an independent element 21a that is soldered to main bolt element 21 at 21b. Element 21a is provided with a threaded hole 23 that is in alignment with threaded opening 20 in wall 19 of barrel 17.

A pin 23a projects into bore 18 at the right end of barrel 17 and is adapted to fit into a slot 23b in bolt element 21a when bolt 21 is withdrawn into barrel 17; this prevents rotation of bolt 21. In order to actuate sliding bolt 21 there is provided a key 24 having a cylindrical shaft 25 of smaller diameter than the minor diameter of threaded opening 20. The extremity of key 24 is provided with external threads 26. Preferably, the internal threads of opening 20 and hole 23 are equivalent and external threads 26 of key 24 are such that key 24 can be screwed through opening 20 and into hole 23 as shown in the figure and key 24 can be withdrawn by unscrewing. Any one of various thread forms can be used to provide desired pitch, diameter and other characteristics.

Operation of the device is as follows. In unlocked position bolt 21 is normally withdrawn to the right from the position shown in the figure and is completely enclosed within barrel 17; in this position pin 23a is disposed in slot 23b. Key 24 is unscrewed from bolt element 21 and barrel 17. In order to lock upper sash 11 with respect to lower sash 12, upper sash 11 is moved to bring barrel 14 into axial alignment with

lower-sash barrel 17 with the result that bores 15 and 18 are in alignment. Key 24 is screwed through opening 20 in barrel 17 and bolt 21 moved to the left into the position shown in the figure either by sliding key 24 to the left in abutting contact with the right end of bolt element 21 or by screwing key 24 into opening 23 and then sliding key 24 and bolt 21 into the left. With bolt 21 in locked position key 24 can be withdrawn by unscrewing the key from bolt hole 23 and barrel opening 20. In order to unlock the device key 24 is screwed through barrel opening 20 and into bolt hole 23 and manipulation of key 24 to the right effects sliding of bolt 21 to the right and retraction thereof out of barrel 14. Turning of key 24 effects rotation of bolt 21 to bring slot 23b into registration with pin 23b. Key 24 is then removed by unscrewing from bolt hole 23 and barrel opening 20.

It is to be understood that various modifications and changes can be made in this invention without departing from the spirit and scope thereof as set forth in the appended claim.

The invention described herein may be manufactured and used by or for the Government of the United States of America for governmental purposes without the payment of any royalties thereon or therefor.

What is claimed is:

A locking device comprising a first element having a cylindrical bore extending therethrough, said bore at one end having a shoulder forming a constriction, internal threads formed in said constriction, a second element having a cylind-

rical bore extending from a surface adjacent the first element partly therethrough, said elements being movable relative to each other to move said bores into and out of alignment, a bolt freely slidably mounted in the bore in the first element, said bolt in extended position being adapted to extend partly into the bore in the second element and in retracted position being adapted to seat against said shoulder, the end of said bolt adjacent the constriction having a bore aligned with the constriction and extending only partly therethrough, internal threads in the bolt bore equivalent to the internal constriction threads, a keyway in said bolt at the end adjacent said constriction, and a pin extending into the bore in said first element adjacent said constriction and adapted to seat in the keyway only when said bolt is fully retracted.
